BALL ROLLING GAME

Donald E. Hooker and Frank G. Nicolaus, Chicago,
Ill., assignors to Raymond T. Moloney, Chicago,
Ill.

Application May 17, 1940, Serial No. 335,658

12 Claims. (Cl. 273—125)

The present invention relates to a ball rolling game of the pin ball type. More particularly it relates to a coin released pin ball game, utilizing more than one playing ball sealed in its cabinet structure.

Such games have a table providing a ball rolling surface on which is located a plurality of scattered obstacles or targets to be hit or bumped by the rolling balls to achieve a score or "win" as it may be called. In a game having five balls available for play it may happen that a score achieved as the result of playing said five balls is just short of achieving a winning score. The player naturally feels that if he could but have another ball to play he could skilfully direct it across the table to engage it with such obstacle as is required to complete the desired win. It so happens, however, with known games of this character that when the allotted number of balls has been played, the balls are trapped out of further play and the game ends.

It is, therefore, desirable to provide means for games of this class, whereby one or more extra balls, that is, over and above the usual allotted number thereof, can be made available for use to the player at his election or option.

Accordingly, the main object of the invention is to provide in a multiple ball, pin ball game, means to make one or more balls available for replay at the election of the player.

Another object is to provide such means operable as the result of movement of the usual coin chute used in releasing these games for play.

Still another object is to provide such means in the form of a novel shuffle board construction.

Another object is to provide an arrangement where as many balls as are sealed in the game may be bought back, so to speak; but only one at a time.

It is also an object to provide a novel shuffle board structure associated with a ball trap "out" pocket at the low end of the game table operable either to drop all balls therein at once to make them available for play; or, to drop but one ball at a time as when using the "buy back" feature of construction.

Another object is to provide an improved control means for regulating the operation of the novel shuffle board structure.

Other important objects will become apparent to those skilled in the art as the disclosure is more fully made.

In a particular and practicable form of the invention herein disclosed the game embodies the usual sealed cabinet containing a table, sloped slightly from the horizontal so that balls rolling on the table surface will eventually gravitate to an "out" pocket at the low end thereof. The cabinet has sealed therein a certain number of

balls, in this instance, five, and at the end of a game play, such balls are held in the said "out" pocket by the shuffle board structure arranged slidably under the pocket. At the start of a game play, a conventional coin chute is coin released and pushed into the cabinet to slide the shuffle board assembly from under the pocket to allow all of the balls to drop into an under trough for delivery by the usual ball lifter onto the table, one at a time, for projection to the table obstacles by means of the usual ball projector. Eventually, these played balls gravitate to the "out" pocket and are held therein by the shuffle board structure arranged therebeneath. If the coin chute is now operated in the usual way all balls in the "out" pocket are dropped at once to the under trough and a game cycle is ended and a new game cycle must be started by the player. However, if the player at his option desires to buy back the balls lodged in the "out" pocket, one at a time, he may do so by manually conditioning an electrical circuit and then operating the coin chute and a part of the shuffle board structure, whereby to drop only one ball from the "out" pocket, for replay. An automatically acting control means makes it possible to perform this replay of balls operation as many times as there are balls sealed in the cabinet, in this instance five. So much will suffice in presenting a general understanding of the improved structure shown in detail in the accompanying sheets of drawings, wherein:

Figure 1 is a reduced scale, general plan view of a typical ball rolling game of the pin ball type;

Figure 2 is an enlarged scale, bottom plan view of the game table in the cabinet, with the improved shuffle board structure shown in its normal ball retaining position with respect to the table "out" pocket, the figure also including a typical wiring diagram for the electrical parts;

Figure 3 is a view similar to Figure 2, but showing the shuffle board structure entirely shifted to a position for dropping all balls from the "out" pocket, at once, as when starting a new game cycle;

Figure 4 is another bottom view, similar to Figure 2, but showing only a portion of the shuffle board structure shifted, as when it is desired to drop only one ball from the "out" pocket;

Figure 5 is a cross sectional view through the shuffle board structure, taken along the line 5—5 of Figure 2, looking in the direction of the arrows;

Figure 6 is a cross sectional view through the structure taken along line 6—6 of Figure 1 and showing in addition the ball lifter and ball projector; and,

Figure 7 is a detail sectional view taken along the line 7—7 of Figure 3.

The game comprises the usual rectangularly shaped cabinet 10 having a front wall 11, an open top closed by a glass panel 12 and a table 13 sloped slightly from the horizontal to provide an inclined ball rolling surface with its low end adjacent the front wall 11. The front wall, at one side, carries a spring plunger, ball projector 14 to shoot a ball through a side passage 15 and along an arch piece 16 on the table to a bumper element 17 from whence the projected ball will rebound and eventually gravitate down the table toward its low end where guide edges 18 direct spent balls to a notched portion 19 delineating an "out" pocket 20, transversely cut through the table 13 at this point, and in this embodiment of a length and size to receive five balls numbered 21. On the surface of the table, in suitable scattered relation, are positioned target or obstacle members 22 of any desired type and intended to be hit or bumped by a rolling ball for score achievement purposes. A slideable coin chute 23 of standard type is positioned in the front wall 11 of the cabinet and its inner end within the cabinet is angularly bent as at 24.

When, upon movement of the shuffle board structure, later to be described, the balls 21 are cleared from the "out" pocket, they drop by gravity into a transverse trough 25 carried in the usual way within the game cabinet. This trough is transversely inclined to cause balls therein to roll toward the right hand or plunger 14, side of the cabinet. At this point the inner face of the wall of the cabinet is formed with an arcuate ball lift passage 26, so that a conventional, pivotally mounted, ball lifter 27, when manually operated by a plunger 28 carried in the front wall 11, as shown, will elevate the balls 21, one at a time into the passageway 15. Here the shooter 14 is effective to propel the balls onto the game table surface in the well known manner. The improved shuffle board structure will now be described.

Figures 2, 3 and 4 all show this structure in bottom plan views. A first and second shuffle board or plate are provided; the first being L-shaped and shown at 29 with one leg thereof extending longitudinally and supported in opposite pairs of carrier rollers 30 mounted on the under side of the table 13. The other leg of the plate 29 is transversely disposed generally below the "out" pocket slot 20 and of a length completely to close off its under side, as shown. A spring 31 connected between the wall 11 and plate 29 normally acts to hold said plate 29 in "out" pocket closing position. At the angle in the plate 29 is provided a shoulder 32 to be abutted by the end 24 on the coin chute 23. The forward edge of the transverse part of the plate 29 carries a thin, forwardly extending divider finger 33 adapted to block off a space at one end of the "out" pocket equal in width to about the diameter of one ball 21. A notch 34 is formed in the piece 18 to accommodate said finger 33 in a manner to be made known.

The rear, or inner end of the longitudinal leg of the first plate 29 has secured to it by a screw pin and slot connection 35, a bar 36, the free end of which by means of a pin 37 has a lever 38 pivotally connected thereto. This lever 38 is pivoted at 39 between its ends to the under side of the table 13. The throw of said lever 38 in one direction is limited by a suitable stop 40. The free end of lever 38 pivotally carries a driver

pawl 41 having a lip portion 42 as shown, and urged by a spring 43 to duty against the teeth of a ratchet wheel 44 turnably mounted on a suitable shaft 45 carried by the table 13. Said shaft and ratchet wheel 44 turn together, step by step, with a conductor wiper arm 46, the free end of which is successively movable over switch contacts 47, of which there are in this instance five, to correspond with the number of balls 21 sealed in the cabinet of the game. A clock type spring 48 is operatively associated with the arm 46 and ratchet wheel 44 so that these latter parts as a unit may be restored to the initial starting position on the first contact button 47. A spring 49 is also connected between the lever 38 and table 13, as shown.

The under side of the table 13 carries a bracket 50 mounting a solenoid 51 having an armature core 52 pivotally connected to one leg of a bell crank dog 53 having a ratchet engaging tooth 20 portion 54 disposed to engage also under the lip 42 of the pawl 41.

The longitudinal leg of the plate 29 has secured thereto as by welding, a bracket 54 carrying an electromagnet 55 having a transversely extending, spring pressed armature core 56, as shown.

In the diagram of Figure 2, a source of electrical energy is shown at 57, a wire 58 leading therefrom to one side of the solenoid 51. From the other side of the solenoid a wire 59 leads to one side of a normally open spring blade contact switch 60 carried from the underside of the table 13 at the location shown. From the other side of said switch, a wire 61 leads back to the source 57. From the wire 61 a wire 62 is led to one side of the magnet core 55 and from the latter a wire 63 leads to connect a series with the contacts 47, arm 46, shaft 45 and by a wire 64 back to the main line 58, all as shown. In the wire 63 is disposed a normally open key or button switch 65 operable manually by a push button 66 preferably positioned on the front wall 11 of the cabinet as shown in Figure 1.

By means of additional rollers 30' the lengthwise leg of a second, or supplementary shuffle plate 67 is supported close to and in parallelism with the longitudinal leg of the first plate 29. Said leg of the plate 67 is positioned for longitudinal movement and in a path to engage with its inner free end portion, the spring blade switch 60 and close it. Said plate 67 includes a wide head portion 67' guided by a slot and pin arrangement 68 for longitudinal shifting motion under the "out" pocket 20 in the table 13. The portion 67' in this instance is of a width to support four balls 21 in the pocket 20. The portion 67' is under the transverse leg portion of the plate 29 and thus the latter rests slidingly on the former. A spring 69 connects between the wall 11 and the plate 67, as shown. The longitudinal leg of the plate 67 carries a bracket 70 providing a downwardly extending notch or shoulder 71 positioned to be engaged normally by the free end of the core 56 so that the two plates 29 and 67 will be interlocked for conjoint sliding movement inwardly into the cabinet to clear balls from the "out" pocket 20. The mode of operation and manner of use of the improved structure will now be described.

In starting the play, all five balls are lodged in the "out" pocket 20 and supported therein from falling through the table 13 to the trough 25 by the presence of the superimposed shuffle board plates 29 and 67', held in pocket closing

position by the pull springs 31 and 69. When the game is released for play the coin chute 23 is pushed into the cabinet and as the coil 55 is de-energized at this time, the two plates 29 and 67 move or shift conjointly against the pull of the springs 31 and 69. In this movement the core 56 is abutting the shoulder 71 as will be obvious. It follows that the overlying transverse portions of the shuffle plates 29 and 67 are shifted to open the bottom of the "out" pocket 20, whereupon all five balls therein must fall by gravity through the table 13 and into the ball trough 25 by which they are directed to the ball lift passage 26 for elevation, one at a time, to the passageway 15 for projection over the table 13 surface by means of the projector 14 all in the well known manner.

As the coin chute 23 is thus pushed in to release the balls, the longitudinal leg of the plate 67 as appears in Figure 7 will ride over the blade switch 60 and close its contacts, thereby causing energization of the coil 61. Consequent movement of its core 52, swings the bell crank 53 to raise the pawl 41 by engaging under its lip 42. This frees the ratchet wheel 44 so that said wheel and its wiper arm 46 are returned by the spring 48 to their initial starting position determined by the stop pin shown but not numbered in Figures 2 and 3, the pin being abutted by the arm 46. Thus, the wiper arm is reset to a position on the first, or right hand contact 47, as viewed in Figure 2.

The five balls are now playable one at a time by using the lifter 28 and projector 14. Eventually, all five balls are again lodged by gravitation into the "out" pocket 20, where they are held because after the game was coin released for play, the springs 31 and 69 promptly restored the plates 29 and 67' to ball holding position under the "out" pocket 20. It will be assumed that the player having scored not quite well enough with his allotment of five balls to achieve a win, feels that if he could but have another ball to play, a win could be achieved. It is here where the present "buy back" structure can be used. The player thus coin releases the coin chute 23, but first presses the switch button 66 to close switch 65. This energizes the electromagnet 55 to retract its core 56 from the shoulder 71 to free or separate shuffle plate 29 from plate 67. As the coin chute 23 is now pushed into the cabinet it is found that the plate 29 alone is moved and the plate 67, 67' remains stationary, and in position to support four balls. As the plate 29 moves back, the one ball 21 at the end of the pocket 20 adjacent finger 33 has no support under it and consequently must fall through the table and into the trough 25 to be made available for play. The plates 29, 67' may be sloped slightly under the pocket 20 in an obvious manner so that a tendency exists for balls in the pocket to roll in the direction of the finger 33 end of the pocket 20. But such slope is not really necessary where heavy steel balls are used as when five are used they always fully occupy the length of the pocket 20, so that one ball is always positioned therein to be dropped singly as described. As the finger 33 moves with plate 29 it acts as a divider to separate the one end ball from the remaining four balls. Thus during the operation just described only the one end ball can be dropped.

Of course, when the plate 29 was so operated alone, its bar 36 worked the lever 38 and pawl 41 to step up the ratchet wheel 44 and move the

arm 46 from the first to the second conductor button 47. By means of this wiper switch 46, 47 the plate 29 can be independently coin released and operated five times as there are five contacts 47. This is just equal to the number of 5 balls 21 it will be noted, so that five balls in all can be separately bought back, so to speak, in an effort to achieve a win. The chances of a player winning are thus augmented. When the arm 46 steps off the last or fifth button contact 47 no 10 current can be passed to energize the electromagnet 55. It follows at this time then, that the two plates 29 and 69 interlock again for conjoint movement, and a new game cycle, releasing all 15 five balls at once, must be started.

Only a preferred example of the invention has been disclosed and obviously it may take many different forms without departing from the spirit and scope of the invention as defined in the appended claims.

What is claimed is:

1. For a ball rolling game having a cabinet carrying a table sloped slightly from the horizontal over which balls are rollable to an "out" pocket formed in the table to receive a predetermined number of spent balls; a shuffle plate structure movably disposed below the table pocket to support the balls therein, means carrying said structure for sliding movement to a position from under the pocket to allow the balls 30 therein to be dropped, said structure comprising two shuffle plates, and optionally operable means to move both plates together conjointly or one plate separately whereby either all or only one of the balls may be dropped from the pocket. 35

2. For a ball rolling game having a cabinet carrying a table sloped slightly from the horizontal over which balls are rollable to an "out" pocket formed in the table to receive a predetermined number of spent balls; a pair of shuffle 40 plates disposed below the pocket to support the balls therein, means carrying said plates for movement to a position from under the pocket to allow the balls therein to be dropped, said plates having superimposed portions disposable 45 in ball supporting position under the pocket with one plate having a width sufficient to support all but one of the balls when arranged in a row in the pocket and both plate portions together supporting all of said balls when in position under 50 the pocket, and means to move the plates conjointly or one independently from under the pocket.

3. For a ball rolling game having a cabinet carrying a table sloped slightly from the horizontal over which balls are rollable to an "out" pocket formed in the table to receive a predetermined number of spent balls; a plurality of shuffle plates disposed slidably below the pocket to support the balls therein, means to couple said plates together to move same conjointly to drop all of said balls through the table, and optionally operable means to uncouple one of said plates for independent movement to drop less than all of the balls from the pocket through the 65 table. 55

4. For a ball rolling game having a cabinet carrying a table sloped slightly from the horizontal over which balls are rollable to an "out" pocket formed in the table to receive a predetermined number of spent balls; a pair of complementary, movably mounted shuffle plates disposed normally under the pocket to support all of the balls therein, means to move said plates conjointly from under the pocket to drop all balls 75 70

therein at once, and means whereby one of said plates is independently movable to drop only one ball at a time from the pocket.

5. For a ball rolling game having a cabinet carrying a table sloped slightly from the horizontal over which balls are rollable to an "out" pocket formed in the table to receive a predetermined number of spent balls; a pair of complementary, movably mounted shuffle plates disposed normally under the pocket to support all of the balls therein, means normally but releasably locking said plates for conjoint movement, means to move the plates conjointly from under the pocket to drop all balls therein at once, means to unlock said plates, and means whereby one of said plates is thereupon independently movable to drop only one ball at a time from the pocket.
- 10
- 15

6. For a ball rolling game having a cabinet carrying a table sloped slightly from the horizontal over which balls are rollable to an "out" pocket formed in the table to receive a predetermined number of spent balls; a pair of complementary, movably mounted shuffle plates disposed normally under the pocket to support all of the balls therein, movable lock means carried by one of said plates for releasably and normally locking said plates for conjoint movement, means to move the plates conjointly from under the pocket to drop all balls therein at once, optionally operable electromagnetic means to move the lock member to unlock the plates and free one thereof for independent movement, and means whereby said latter one plate is movable independently to drop only one ball at a time from the pocket.

7. For a ball rolling game having a cabinet carrying a table sloped slightly from the horizontal over which balls are rollable to an "out" pocket formed in the table to receive a predetermined number of spent balls; a pair of complementary, movably mounted shuffle plates disposed normally under the pocket to support all of the balls therein, movable lock means carried by one of said plates for releasably and normally locking said plates for conjoint movement, means to move the plates conjointly from under the pocket to drop all balls therein at once, optionally operable electromagnetic means to move the lock member to unlock the plates and free one thereof for independent movement, means whereby said latter one plate is movable independently to drop only one ball at a time from the pocket, and a single manually operable member common to the plates for so moving them conjointly or relatively.

8. For a ball rolling game having a cabinet carrying a table sloped slightly from the horizontal over which balls are rollable to an "out" pocket formed in the table to receive a predetermined number of spent balls; a pair of complementary, movably mounted shuffle plates disposed normally under the pocket to support all of the balls therein, movable lock means carried by one of said plates for releasably and normally locking said plates for conjoint movements, means to move the plates conjointly from under the pocket to drop all balls therein at once, optionally operable electromagnetic means to move the lock member to unlock the plates and free one thereof for independent movement, means to move said latter one plate independently to drop only one ball at a time from the

pocket, and an electromechanically operated control means to limit the number of operations the independently movable plate is capable of having.

9. For a ball rolling game having a cabinet carrying a table sloped slightly from the horizontal over which balls are rollable to an "out" pocket formed in the table to receive a predetermined number of spent balls; a pair of complementary, movably mounted shuffle plates disposed normally under the pocket to support all of the balls therein, means to move said plates conjointly from under the pocket to drop all balls therein at once, means whereby one of said plates is relatively and independently movable to drop only one ball at a time from the pocket, and control means responsive to operation of said latter one plate to limit the number of independent operations said plate is capable of having. 15 20

10. For a ball rolling game having a cabinet carrying a table sloped slightly from the horizontal over which balls are rollable to an "out" pocket formed in the table to receive a predetermined number of spent balls; a pair of complementary, movably mounted shuffle plates disposed normally under the pocket to support all of the balls therein, means to move said plates conjointly from under the pocket to drop all balls therein at once, means whereby one of said plates is relatively and independently movable to drop only one ball at a time from the pocket, and electromechanical control means operative in response to movement of the latter plate to limit the number of operations thereof to not more than the predetermined number of balls used in the game. 30

11. For a ball rolling game having a cabinet carrying a table sloped slightly from the horizontal over which balls are rollable to an "out" pocket formed in the table to receive a predetermined number of spent balls; a shuffle plate structure comprising two movably mounted members carried by the table and having superposed portions adapted to be positioned under the pocket to support the balls therein, said portions being of different widths relative to the length of the pocket with one at least as wide as the pocket is long and the other being somewhat shorter than the pocket is long, and means to move the portions together from under the pocket or one portion alone 40 45 50

12. For a ball rolling game having a cabinet carrying a table sloped slightly from the horizontal over which balls are rollable to an "out" pocket formed in the table to receive a predetermined number of spent balls; a shuffle plate structure comprising two shiftable plates carried by the table and positionable under the pocket to support the balls therein, means to move the plates conjointly from under the pockets to release all balls at once, means whereby one of the plates is shiftable individually whereby to release less than all the balls, electrical control means movable step by step from an initial starting position each time the one plate is individually shifted to limit the number of operations the said plate can have, and means for resetting said control means to starting position when the two plates are conjointly shifted. 55 60 65 70
